UNITED STATES PATENT OFFICE

REGINALD HOWARD BAKER AND CECIL WILLIAM PARSONS, OF ASTON, BIRMINGHAM,
ENGLAND

ELECTRIC SWITCH

Application filed July 29, 1929, Serial No. 381,859, and in Great Britain November 7, 1928.

This invention has for its object to provide a simple and robust electric switch of the type commonly termed a "ceiling switch", that is to say, a switch which is adapted to be actuated through the medium of a cord, or chain.

The invention comprises the provision of a rocking member in conjunction with a suitable toggle or lever mechanism carrying the movable contact or contacts, and the employment of an operating element which is pivotally mounted on a spring controlled and cord or chain actuated sliding piece, the said element being so constructed and arranged that it can automatically engage in a hook like or equivalent manner with either end of the rocking member for the purpose of effecting an operative connection between the sliding piece and rocking member.

In the accompanying sheet of explanatory drawings:—

Figures 1 and 2 are sectional front views (in two positions), and Figure 3 a sectional end view of a switch constructed in accordance with this invention.

In carrying the invention into effect as shown, we employ any suitable toggle mechanism in combination with the movable contacts. In the switch illustrated the movable contacts *a* are carried by pivoted side arms *b* and are movable with respect to fixed contacts *c*. The arms are movable by a toggle mechanism comprising a pair of pivotally connected parts *d*, *e*, the latter of which can actuate the arms *b* through a spring *f* and pressure piece *g*. All this mechanism is known and forms no parts of our invention. The part *d* which can oscillate about the pivot pin *h* has formed with or secured to it a rocking member *i* having a pair of ends which are formed with end gaps *i'* for engagement by the operating element *j*. The operating element is situated transversely across the rocking member *i*, and consists of a piece which is pivoted at its centre and is formed with hook like ends *k*. The pivotal connection between the operating element *j* and a sliding piece *l* is effected through the medium of a short link *m*, the operating element being pivoted on the link, and the latter being pivoted on the sliding piece.

The sliding piece *l* is arranged to move within a hollow tubular guide *n*, and a strong helical spring *o* is situated within the guide to move the sliding piece and operating element in the direction of the rocking member. The operative movement for either opening or closing the switch is imparted to the sliding piece *l* by means of a chain *p*, cord or the like, attached to the link *m* at a position beneath the pin *q* whereby the link *m* is pivoted on the sliding piece *l*.

Starting with the operating element in the position shown in Figure 1, a pull on the chain causes the said member to be rocked over from one limiting position to the other for opening or closing the switch. It will be noticed that when there is no pull on the chain, the active hook *k* on the member *i* may not fully engage the adjacent gapped end of the part *i* as shown in Figure 1, the active end being that at the left hand side of the drawing. But as soon as a pull is exerted on the chain, the first effect is to cause a secure interengagement of *k* and *i*, and so long as the tension is maintained, those parts remain securely connected, the right hand end of the operating element being clear of the right hand end of the rocking member *i*. After the member *i* has been rocked over by the operating element *j*, thereby causing a complete movement to be given to the movable contact, and on relaxing the pull on the chain, the sliding piece *l* returns under the action of its spring, and during this movement the operating element becomes disconnected from the end of the rocking member which it formerly engaged and is rocked over by its contact with the now stationary rocking member so as to bring its other end into engagement with the other end of that member. This condition is shown in Figure 2, and the switch is now ready for a reverse movement of the movable contact.

The invention is not limited to any particular subordinate details of construction, as these may be varied as required. In the switch illustrated a slotted part *r* is shown. The purpose of this is to provide a guide for the rocking member, the latter being arranged to slide within the slots in the said

part. This feature, though convenient, is not essential.

Having thus described our invention what we claim as new and desire to secure by Letters Patent is:—

- 5 1. In electric switches of the kind specified, the combination comprising a movable contact, a toggle mechanism carrying said contact, a rocking member connected with the toggle mechanism, a sliding piece, a spring for imparting to the sliding piece a movement in one direction, an operating element cooperating with the rocking member, a link pivotally connecting the operating element and sliding piece, and means attached to the link for imparting to the sliding piece a movement in the opposite direction to that effected by the spring, said element having two hook-like pieces adapted alternately to engage the ends of the rocking member, substantially as described.
- 10 2. In electric switches of the type specified, the combination comprising a movable contact, a toggle mechanism carrying said contact and including a spring, a rocking member connected with the toggle mechanism, a sliding piece, a fixed hollow guide slidably receiving said piece, a spring for imparting to the sliding piece a movement in one direction, a link having one end pivoted on the sliding piece, means attached adjacent the pivotal connection of the link and sliding piece for imparting to the sliding piece a movement in the opposite direction to that effected by the spring, and an operating element pivoted on the outer end of the link and comprising two hook-like portions, said parts being adapted alternately to engage the ends of the rocking member, substantially as described.
- 15 3. In testimony whereof we have signed our names to this specification.
- 20 REGINALD HOWARD BAKER.
CECIL WILLIAM PARSONS.
